CLAIM

The ornamental design for an electronic display unit, as shown and described.

DESCRIPTION

1. Electronic display unit

1.1 : Perspective

1.2 : Rear perspective view

1.3 : Front

1.4 : Back

1.5 : Left

1.6 : Right

1.7 : Top

1.8 : Bottom

1.9 : Enlarged

The reproduction 1.9 is an enlarged view of a portion of the reproduction of 1.2 represented by the square in dash-dot lines and curvy line and the number 1.9; the broken lines indicate portions of the article that form no part of the claimed design.

1 Claim, 9 Drawing Sheets(56)
